UNITED STATES PATENT OFFICE.

CARL H. TRIESCHMANN, OF MILWAUKEE, WISCONSIN.

ARCH SUPPORT.

Application filed July 21, 1924. Serial No. 727,221.

To all whom it may concern:

Be it known that I, CARL H. TRIESCHMANN, a citizen of the United States, and resident of Milwaukee, in the county of Milwaukee and State of Wisconsin, have invented new and useful Improvements in Arch Supports, of which the following is a description, reference being had to the accompanying drawings, which are a part 10 of this specification.

This invention relates to improvements in arch supports, and more particularly to adjustable arch supports.

It is one of the objects of the present invention to provide an arch support constructed to permit the wearer to quickly and accurately adjust the same to meet the requirements of his foot, the arch support being formed with an adjustable, movable, 20 flexible and elastic cushion or pad confined within a certain necessary radius between two or more layers of leather or other suitable material to support the anterior transverse arch.

25 A further object of the invention is to provide an adjustable arch support formed with a trimming edge to permit the insole to be trimmed to exactly fit a shoe, the stitching on the insole being designed to 30 permanently hold the material together and positioned so that the edges may be trimmed without cutting the stitches, or in any manner interfering with the adjustable advantages and efficiency of the arch support.

35 A further object of the invention is to provide an arch support of the class described formed with an opening through the bottom of the insole in juxtaposition with the pad, the opening serving to hold 40 the pad in position due to a portion of the pad being forced into the opening by pressure of the foot, and also permitting the insertion of a sharp tool to shift the position of the pad when desired.

45 A further object of the invention is to provide a nonmetallic arch support, which is perfect fitting, effective, and always comfortable.

50 A further object of the invention is to provide an adjustable arch support which is of very simple construction, is inexpensive to manufacture, is strong and durable, and is well adapted for the purposes described.

55 With the above and other objects in view the invention consists of the improved ad-

justable arch support and its parts and combinations as set forth in the claim, and all equivalents thereof.

In the accompanying drawing in which 60 the same reference characters indicate the same parts in all of the views:

Fig. 1 is an inverted plan view of the improved adjustable arch support;

Fig. 2 is a longitudinal sectional view 65 thereof taken on line 2—2 of Fig. 1;

Fig. 3 is a cross sectional view thereof taken on line 3—3 of Fig. 1; and

Fig. 4 is a fragmentary view illustrating 70 a slight modification of the invention.

Referring now more particularly to the drawing it will be seen that the numeral 8 indicates the improved arch support, the same being in the form of a shoe insole and consisting of a top portion 9 and a bottom 75 portion 10, both being formed of leather or other suitable material. The top and bottom portions 9 and 10 are secured together, entirely therearound by stitching, as at 11, and the edge portions may also be cemented, 80 if desired.

It will thus be seen that a pocket 12 is formed in said insole between the two portions 9 and 10, and in said pocket, near the forward wider end of the insole, a pad or 85 cushion member 13 is positioned. Said pad is preferably of rounded form as shown in Figs. 2 and 3 and is formed of sponge rubber, or any other suitable yielding material. The flat face 14 of the pad is positioned adjacent the bottom portion 10 of the insole, and said bottom portion 10 is formed with one or more openings 15, of small size and preferably shaped as shown. The openings 15 permit the insertion of a small tool to 90 shift the position of the pad to meet the requirements of the wearer's foot and by shaping the openings as shown only a very small area of the pad is exposed while a relatively large transverse or longitudinal adjustment 100 of the pad may be attained. The openings 15 also serve the purpose of holding the pad in position after it has been adjusted, due to the fact that the pressure of the foot will force a small portion of the pad into the 105 opening or openings. Obviously, the openings 15 may be of any desirable number, and in Fig. 4, an insole formed with three such openings 15 has been shown.

It should be observed that the line of 110 stitching 11 is spaced from the edges of the insole. This permits the size of the insole

to be reduced by trimming if the insole is a trifle too wide for the shoe in which it is to be used. Also the stitching is so positioned that it will permanently hold the material together and if trimming is necessary, the stitches will not be cut, nor will any of the adjustable advantages of the support be interfered with.

In use, the support is readily insertable in a shoe, and the openings 15 permit the insertion of an awl or needle to reach the pad whereby it can be quickly moved to locate its elevation at exactly the required position under the ball of the foot. After that the tool is withdrawn and the pad is permanently held in position as described, until, or unless further adjustments become necessary, or a change of location is desired.

From the foregoing description it will be seen that the improved adjustable arch sup-

port is of very simple and novel construction, and is well adapted for the purposes set forth.

What I claim as my invention is:

An adjustable arch support, comprising a leather insole member formed with a bottom layer and a top layer secured together by a line of stitching spaced from the edges of said portions to provide a pocket between the layers and to permit the insole edges to be trimmed, and a yielding, non-removable pad member within said pocket, one of said insole layers having a cross-shaped opening therein engaging said pad member and permitting the insertion of a tool for the purpose of adjusting said pad member within the pocket.

In testimony whereof, I affix my signature.

CARL H. TRIESCHMANN.
